UNITED STATES PATENT OFFICE.

ERNEST N. HUMPHREY, OF NEW BRITAIN, CONNECTICUT, ASSIGNOR TO THE TRAUT AND HINE MANUFACTURING COMPANY, OF NEW BRITAIN, CONNECTICUT, A CORPORATION OF CONNECTICUT.

SAFETY-RAZOR.

1,076,579.

Specification of Letters Patent.

Patented Oct. 21, 1913.

Application filed December 5, 1911. Serial No. 663,677.

To all whom it may concern:

Be it known that I, ERNEST N. HUMPHREY, a citizen of the United States, residing at New Britain, Hartford county, State of Connecticut, have invented certain new and useful Improvements in Safety-Razors, of which the following is a full, clear, and exact description.

My invention relates to safety razors, and 10 particularly to a new construction whereby the several parts may be easily assembled and dismembered.

In the drawings, Figure 1 is a perspective view of the safety razor. Fig. 2 is a plan view of the parts shown in Fig. 1, said view being relatively enlarged. Fig. 3 is a view of the under side of the head end shown in Fig. 1 with the handle removed. Fig. 4 is a central longitudinal section through the 20 head of the razor. Fig. 5 is a view similar to Fig. 4 with the razor open.

1 represents a combined blade support and guard plate having the usual guard fingers 2-2 at opposite edges.

25 3 represents a threaded shank at the back of the plate 1.

4 is a handle arranged at one end to screw onto the shank 3.

5 is a plate having at its forward end a 30 slot which overstands the threaded shank 3 and is located between the end of the handle 4 and the back of the plate 1. The other end of this plate 5 is hinged at 6-6 to one end of an outside keeper plate 7.

35 8 is a razor blade, in this instance double edged, and being of an appropriate size to properly fit between the plates 1 and 7. In this particular instance the positioning lugs for the blade to prevent endwise and lateral

40 displacement thereof are formed wholly on the plate 7, although the particular arrangement of said positioning lugs is immaterial. In the preferred form shown in the drawings, these positioning lugs are formed by 45 turning down the ends of the plate 7 to form the end pieces 9-9^a, said end pieces being provided at each edge with lugs 10-10 to properly embrace and position the blade 8.

50 11 is a positioning lug on the back of the plate 1, said lug being preferably slightly hooked at its end and passing through a slot in the plate 5.

55 12-12 are lugs at the end of the plate 1 opposite the lug 11. In this instance, two

of these lugs 12 are provided. The end wall 9 of the plate 7 is recessed or perforated to receive the lugs 12-12, as shown in all of the figures excepting Fig. 5.

From the foregoing it will be seen that 60 when the parts of the razor blade holder stand as shown in Fig. 5, the blade 8 may be readily inserted. As soon as this blade is in position, the plate 7 may be swung down until the recesses or perforations in the end 65 piece 9 face up with the lugs 12. When this occurs, the plate 1 is slid, relatively to the plate 7, in a direction to cause the lugs 12 to enter the notches or recesses in the end piece 9. It is now obvious that when the 70 parts stand in this position, the plates 1-7 are locked together to hold the blade and cannot be unlocked until the plate 1 is slid back so as to disengage the lugs 12. To prevent this accidental slipping back, the 75 handle 4 is turned in a direction to clamp the plate 5 tightly between itself and the back of the plate 1.

In Fig. 4 I have shown the parts assembled and the handle screwed partially down. 80 In this position it will be seen that by turning the handle slightly more, the plate 5 will be clamped as aforesaid, whereupon the plate 1 cannot slide relatively to the plate 5, and since said plate 5 is secured to the 85 end 9^a of the plate 7, it follows that all of the parts are locked together securely for use.

It is obvious that all of the parts may be 90 readily separated for the removal or cleaning of a used blade, and may be as quickly assembled for the purpose of receiving and positioning a new blade.

What I claim is:

1. In a safety razor, the combination of 95 two plates arranged to embrace between them a blade, interlocking means for said plates, said means being moved into interlocking position by a sliding movement of one of said plates relatively to the other in 100 a direction parallel to the other, a member hinged to the forward one of said plates and means engaging the other of said plates and said member to prevent relative sliding movement of said two plates out of interlocking position when the same embrace a blade ready for use.

2. In a safety razor, the combination of 105 two plates arranged to embrace between them a blade, interlocking means for said 110

plates, said means being moved into interlocking position by a sliding movement of one of said plates relatively to the other in a direction parallel to the other, a member 5 hinged to the forward one of said two plates and means engaging the other of said two plates and said member to prevent relative sliding movement of said two plates out of interlocking position when the same embrace 10 a blade ready for use, said interlocking means being formed integrally with said plates.

3. In a safety razor, the combination of two plates arranged to embrace between them a blade, interlocking means for said plates, said means being moved into interlocking position by a sliding movement of one of said plates relative to the other in a direction parallel to the other, a member 20 hinged to the forward one of said two plates and means engaging the other of said two plates and said member to prevent relative sliding movement of said two plates out of interlocking position when the same embrace 25 a blade ready for use, and blade centering means on one of said plates.

4. In a safety razor, the combination of a keeper plate having downturned projections, a guard plate having a projection on one 30 end, the length of said guard plate including said projection not exceeding the distance between said downturned projections, the downturned projection adjacent to the pro-

jection on the guard plate having an opening for said last named projection, a slotted plate at the rear of said guard plate permanently connected to the other downturned projection, a screw secured to the guard plate and passing through the slot in said slotted plate, and a handle on said screw adapted to clamp said slotted plate against said guard plate.

5. In a safety razor, a guard plate, a threaded shank at the back of said plate, a device arranged to screw onto said shank, a 45 plate at the rear of said guard plate having a slot through which said shank passes, a keeper plate hinged to said slotted plate at one end of said guard plate, said guard plate and keeper plate being arranged to embrace 50 between them a blade, interlocking means at the end of the keeper plate and guard plate opposite to the aforesaid hinged connection, said interlocking means being engageable and disengageable by a sliding movement of 55 said guard plate relatively to said slotted plate and keeper plate, the screw threaded means mounted on said shank being arranged to clamp the slotted plate between itself and the back of the guard plate to 60 prevent sliding movement of one plate relatively to the other.
